United States Patent Office

Des. 178,593
Patented Aug. 28, 1956

178,593

CONTAINER FOR USE WITH A BLENDER

Frank E. Cerveny, Berwyn, and Sigmund R. Kukulski, Chicago, Ill., assignors to Sunbeam Corporation, Chicago, Ill., a corporation of Illinois

Application October 17, 1955, Serial No. 38,408

Term of patent 14 years

(Cl. D89—1)

Fig. 1.

Fig. 2.

Fig. 3.

Fig. 4.

Fig. 5.

Fig. 1 is a perspective view of a container for use with a blender embodying our new design;

Fig. 2 is a side elevational view of the container of Fig. 1;

Fig. 3 is a front elevational view of Fig. 2;

Fig. 4 is a top plan view of Fig. 3; and

Fig. 5 is a bottom plan view of Fig. 3.

The dominant features of our design reside in the portions shown in full lines.

We claim:

The ornamental design for a container for use with a blender, substantially as shown and described.
